(57) **CLAIM**

The ornamental design for a medical gown, as shown and described.

DESCRIPTION

FIG. 1 is a front elevation view of a first embodiment of a medical gown illustrating our new design in an untied configuration;

FIG. 2 is a rear elevation view thereof;

FIG. 3 is a rear elevation view of the medical gown with left and right flaps in a lifted state to expose the interior surface; FIG. 4 is a front elevation view of a second embodiment of a medical gown illustrating our new design in an untied configuration;

FIG. 5 is a rear elevation view thereof; and,

FIG. 6 is a rear elevation view of the medical gown with left and right flaps in a lifted state to expose an interior surface. The long dash broken line between the neck and opening along the back of the gown is a perforation and forms part of the claimed design. The dot-dash broken lines in Embodiment 2 represent the bounds of the claimed design and form no part of the claimed design. The short evenly spaced broken lines in Embodiment 2 are directed to environment and form no part of the claimed design.
